VISIBLE CARD INDEX FILE

James F. Foley and Frederick C. Gleason, New York, N. Y., assignors to Remington Rand Inc., New York, N. Y., a corporation of Delaware

Application November 7, 1950, Serial No. 194,526

4 Claims. (Cl. 129—16)

1

This invention relates generally to visible index card files and in particular to an inclined file rack having plural visible index card supporting trays pivotally mounted therein in stepped index-displaying relation.

The invention is particularly adaptable for use in centrally located reservation systems, such as used by railroads, airlines or steamship companies, wherein it is desirable that a maximum of recorded data be visibly available for instantaneous selection. Essentially, the invention consists of a sheet metal frame having a base, opposing side walls, provided with inclined upper edges, a front wall, a rear wall and a recessed inclined floor or base secured within said walls. These elements are so assembled as to form a light weight, rigid, unitary structure. Arranged to be pivotally mounted on the frame side walls and disposed in spaced alignment with the inclined base are plural visible index card supporting trays.

Uniformly dimensioned trays are vertically stepped to provide for a visible area at the upper margin of each tray in which index card tabs may be readily viewed. Further, by employing cards having laterally offset tabs thereon, the display area of each tray can accommodate several tabs. All of the laterally disposed tabs are readily visible, therefore, the selecting of a particular card is greatly facilitated. It is proposed that each tray contain a like number of cards with similarly disposed tabs in order to produce a columnar relation between the respective trays.

The data-bearing cards are supported in each tray in a substantially vertical position by means of an upwardly extending face portion, a rearwardly extending projection disposed at the base thereof and the upwardly extending face portion of the next higher tray.

The projection extends rearwardly under the base of the next higher tray, therefore, in addition to acting as a supporting shelf for the cards, the said projection limits forward pivotal movement of the tray. The uppermost tray cooperates with a fixed plate in an analogous manner. The projections are disposed relative to the base of the next higher tray so as to permit a limited degree of movement forwardly of the perpendicular. In a like manner, the spacing between trays allows limited movement rearwardly of the perpendicular. Thus, manual forward displacement of a selected tray concurrently displaces all trays in front thereof without disturbing the upper or rear trays. This separation facilitates the removal of a card from the selected tray. The removed card may be returned without difficulty since the balance of the cards are gravitationally retained in either the displaced position or the normal position.

2

Should the trays be disturbed prior to the returning of the selected card, visual scanning of the entire file will locate the proper filing place by means of the obviously apparent blank area normally occupied by the tab of the selected card.

In the drawings:

Figure 1 is a front elevational view of the invention with a portion cut away to show the inclined recessed base.

Fig. 2 is a sectional view taken along line 2—2 of Fig. 1 looking in the direction of the arrows.

Fig. 3 is a perspective view of the rack generally without cards and illustrating the front trays in forwardly inclined position to provide a tray separation.

Fig. 4 is a sectional detail illustrating the method of securing a tray within the rack.

Referring to the Figs. 1, 2 and 3, the invention comprises a rack or frame 10 fabricated of sheet metal members to define opposing side walls 12 and 14, a front wall 16, a rear wall 18, a base 20 and an inclined base or floor member 22.

The respective sheet metal members are secured in assembled relation by means of welding or the like to provide a substantially rigid, unitary structure. As shown in Figs. 2 and 3, the side walls 12, 14 are provided with horizontally disposed base edges, vertical front and rear edges and downwardly inclined upper edges. Inclined base 22 is secured thereto in parallel relation with and spaced below or recessed from the inclined upper edges thereof. Thus, front wall 16, rear wall 18, inclined base 22 and the portions of side walls 12, 14 extending thereabove combine to provide an inclined housing for visible index card supporting trays 24.

Trays 24 are analogously formed from sheet metal blanks and consist of an upwardly extending face portion 26, a rearwardly extending projection 28 and a sleeve 30. The projection 28 is formed by a double fold of sheet metal disposed at substantially right angles to the lower terminal of face portion 26 and has the tip portion thereof bent upwardly as at 32. The sleeve 30 is a continued formation of the projection and is disposed centrally thereunder. Secured within sleeve 30 and extending laterally therefrom are pins 34 which provide a means for the pivotal securing of trays 24 in the rack 10.

Panels 36, 38, secured to the inner surfaces of side walls 12 and 14, respectively, co-act to pivotally mount trays 24 thereon. As shown in Figs. 2 and 4, the upper lateral edges of panels 36, 38 are secured to the inclined edge portions of the respective side walls and extend angularly therefrom to provide card guide means. Portions of panels 36, 38, are spaced from and parallel to side walls 12, 14 and have perforated therein complementary rows of apertures 40. The rows of

apertures 40 are linearly disposed parallel with the inclined edges of side walls 12, 14. Further, the trays are arranged to be positioned substantially upright with pins 34 journaled in the opposing apertures 40.

When assembled in this manner, projection 28 of the lowermost tray 24 extends rearwardly under sleeve 30 of the next higher tray. Projections 28 of the remaining trays are similarly disposed. Pivotal movement forwardly of each tray is therefore limited by means of the projection tip 32 abutting against the adjacent higher tray. The projection 28 of the uppermost tray 24 is disposed under fixed plate 42 having a sleeve-like base 44. Plate 42 is secured at the upper end thereof to the frame rear wall 18.

Rearward movement of the individual trays 24 is similarly limited by means of plate 42, i. e., the rear of the face portion of the uppermost tray 24 abuts thereagainst and subsequently each face portion of the lower trays abuts against the adjacent higher tray and is stopped thereby.

Cards 46, having index tabs 48 projecting upwardly therefrom, are arranged to be positioned upright in pockets formed by adjacent tray face portions and rest on the projections 28 therebetween. When disposed on the trays, cards 46 are arranged in a predetermined order.

In the particular embodiment shown in the drawings, each tray 24 is arranged to receive six cards therein. The tabs 48 of the respective cards are spaced in lateral offset relation and are visibly displayed above the upwardly extending portion of tray 24. When in this position the upper edges of the tabs 48 align with the upper edge of the next higher tray, therefore the tabs of cards disposed in all trays are similarly clearly visible.

Secured to the face of the lowermost tray 24 and disposed in columnar relation to tabs 48, is an indicia holder 50 in which columnar heading indicia may be detachably secured.

Operationally, the invention presents a simple, highly efficient visible index card filing system. When a particular card is desired, it is only necessary to glance at the columnar heading followed by a rapid scanning of the indicated column. Subsequent manual forward displacement of the tray holding the desired card effects the forward movement of all lower trays. The chosen card may be then readily removed, inspected and returned to the correct tray since all trays below are disposed forwardly of the perpendicular and all trays above are reclining rearwardly of the perpendicular. The separation effected thereby is readily ascertained, therefore, filing errors are substantially eliminated. Should it be necessary to remove two or more cards from differing trays at the same time, the said cards may be returned to their correct trays by merely scanning the overall file and locating the obvious blank space.

The invention claimed is:

1. A filing rack for visible index cards comprising a frame formed from sheet metal blanks to provide substantially triangular shaped side walls having generally inclined upper edges, offset front and rear walls, a base and an inclined floor disposed parallel to and spaced from the inclined upper edges of said side walls, plural card holding trays each having a substantially upright face portion, an integrally formed projection rearwardly extending from the base thereof and a sleeve integrally formed therewith and disposed under said projection, members secured to said sleeve and marginally ex-

tending therefrom, tray supporting panels disposed against the interior of said side walls and secured thereto, plural apertures linearly disposed in spaced alignment in said panels, said 5 marginally extending members adapted and arranged to pivotally secure said trays within said apertures with the projections thereon extending rearwardly beneath the next higher tray sleeve whereby pivotal movement of said trays is limited.

2. A filing rack for visible index cards comprising a frame formed from sheet metal blanks to provide side walls having generally inclined upper edges, offset front and rear walls, a base and an inclined floor disposed parallel to and spaced from the inclined upper edges of said side walls, plural card holding trays each having a substantially upright face portion, a right angularly disposed projection rearwardly extending from the base thereof and a sleeve centrally disposed thereunder, pins secured to said sleeve and marginally extending therefrom, tray supporting panels disposed against the interior of said side walls and secured thereto, plural apertures linearly disposed in spaced alignment in said panels arranged to receive said pins to pivotally mount said trays in stepped relation, each of said trays being substantially balanced whereby forwardly pivotal movement of a selected tray past the perpendicular effects a similar pivotal movement of all lower trays with each rearwardly extending projection coacting with the next higher tray to limit said forward pivotal movement.

3. A filing rack as set forth in claim 2 wherein pivotal movement of the uppermost card-holding tray is limited by a fixed plate secured to the rear wall of the frame.

4. A filing rack for visible index cards comprising a frame formed from sheet metal blanks to provide side walls having generally inclined upper edges, offset front and rear walls, a base and an inclined floor disposed parallel to and spaced from the inclined upper edges of said side walls, plural card holding trays each having a substantially upright face portion, an integrally formed projection rearwardly extending from the base thereof and a sleeve integrally formed therewith and disposed under said projection, means secured to said sleeve and marginally extending therefrom, tray supporting panels disposed against the interior of said side walls and secured thereto, plural apertures linearly disposed in spaced alignment in said panels, said means adapted and arranged to pivotally secure said trays within said apertures with the projections thereon extending rearwardly beneath the next higher tray sleeve whereby the upright face portion and projection of one tray cooperates with the upright face portion of the next higher tray to retain cards disposed therebetween in a substantially vertical index-displaying position.
